Primary Examiner — Ricky Pham(74) *Attorney, Agent, or Firm* — Hitchcock Evert LLP(57) **CLAIM**

The ornamental design for a round perforated pan, as shown and described.

DESCRIPTION

FIG. 1 is a perspective view from the top of the round perforated pan;

FIG. 2 is a front view thereof;

FIG. 3 is a back view thereof;

FIG. 4 is a right side view thereof;

FIG. 5 is a left side view thereof;

FIG. 6 is a top view thereof; and

FIG. 7 is a bottom view thereof; and,

FIG. 8 is a perspective view from the bottom thereof.

The dotted lines are for illustrative purposes only and form no part of the claimed design.
